UNITED STATES PATENT OFFICE.

JOHN A. ANDERSON, OF MINNEAPOLIS, MINNESOTA.

ADJUSTING MECHANISM FOR GANG-PLOWS.

1,169,451.

Specification of Letters Patent. Patented Jan. 25, 1916.

Application filed August 14, 1912. Serial No. 715,125.

To all whom it may concern:

Be it known that I, JOHN A. ANDERSON, a citizen of the United States, residing at Minneapolis, in the county of Hennepin and State of Minnesota, have invented certain new and useful Improvements in Adjusting Mechanism for Gang-Plows; and I do hereby declare the following to be a full, clear, and exact description of the invention, 10 such as will enable others skilled in the art to which it appertains to make and use the same.

My invention relates to traction gang plows and more particularly to traction 15 gang plows of that type wherein the plows are connected to and carried by the frame of the traction engine.

The invention has for its especial object the provision of improved means for raising 20 and lowering and otherwise adjusting the plows; and to such ends, generally stated, the invention consists of the novel devices and combinations of devices hereinafter described and defined in the claims.

25 In the accompanying drawings which illustrate the invention, like characters indicate like parts throughout the several views.

Referring to the drawings, Figure 1 is a 30 plan view showing my invention embodied in a combined traction engine and gang plow, some parts being broken away, and some parts being removed; Fig. 2 is a side elevation of the parts shown in Fig. 1, some parts being broken away, and some parts 35 being sectioned; Fig. 3 is an enlarged transverse vertical section taken on the line $x^3 x^3$ on Fig. 1, some parts being broken away; Fig. 4 is a detail in side elevation showing parts found in the vicinity of the line 40 marked $x^4 x^4$ on Fig. 1, some parts being broken away; Fig. 5 is a section taken approximately on the line $x^5 x^5$ on Fig. 1, some parts being broken away; and Fig. 6 is a section taken approximately on the line 45 $x^6 x^6$ on Fig. 1, some parts being broken away.

50 So far as my present invention is concerned, the traction engine proper may take various different forms and the transmission mechanism between the engine and the traction wheels of the tractor may be of any suitable construction. Hence, the main elements of the tractor proper may be briefly noted as follows:

55 The numeral 1 indicates an approximately

horizontal skeleton framework which is intermediately supported on a rear axle 2 having large traction wheels 3. The front portion of the frame 1 is carried in the usual or any suitable way by a front axle and by 60 front steering wheels 4, which latter are indicated only in part. The numeral 5 indicates a multi-cylinder explosive engine carried on the main frame 1 and connected to large driving sprockets 6 on the hubs of 65 the traction wheels 3, through intermediate transmission mechanism of suitable construction indicated as an entirety by the numeral 7.

In the tractor, as illustrated, four plows 8 70 are employed, but the number of these plows may be varied at will, and the plows may be connected individually or in pairs, to plow beams 9, the front ends of which are connected to a depending intermediate portion 75 of the tractor frame, with freedom for pivotal movements and with freedom for vertical adjustments at their front ends. In the present connection, as illustrated, the frame member to which the front ends of 80 the plow beams are anchored, is in the form of an oblique metal beam 10, rigidly secured to the main frame 1 by connecting brackets 11 and 12. The perforated heads 9^a on the front ends of the plow beams 9 are directly 85 pivoted to anchor blocks 13 mounted to move vertically on anchor posts 14 rigidly secured at their upper and lower ends to anchor brackets 15 rigidly secured to the oblique beams 10. The vertically adjustable so-called anchor blocks 13 are provided on the 90 front edges with rock teeth that mesh with gear segments 16 secured on a rock shaft 17, which, in turn, is journaled in suitable bearings 17^a on the oblique beams 10. This rock 95 shaft 17 (see particularly Figs. 2 and 3) is provided with an adjusting arm 18 that works through a bifurcated segment 19 secured on the beams 10. This segment 19 has a series of perforations through any of 100 which a stop pin or bolt 20 may be passed to limit the downward movement of the several anchor blocks 13.

The free end of the lever 18 is attached to the lower end of a chain or other cable 21, 105 which, as shown, is passed over an idle guide sheave 22 and is anchored to and adapted to be wound upon a windlass drum 23. The idle sheave 22 is journaled to a bearing 24 on the frame 1, and the drum 23 is loose on 110

one section 25 of a longitudinally divided shaft 25—26, which shaft is journaled in suitable bearings 27 on the frame 1.

The numeral 28 indicates a double conical ended clutch sleeve that is keyed or otherwise rigidly secured to one end of the shaft section 25 and into the hub of which, as shown, the end of the shaft section 26 is loosely telescoped.

10 The numerals 29 and 30 indicate friction cones that frictionally engage, one with each end of the clutch sleeve 28. The cone 29 is rigidly secured to one end of the windlass drum 23 and a cone 30 is connected to the 15 shaft section 26 for sliding movements thereon but for rotation therewith, by a key 31 (see Fig. 5). A spring 32 interposed between the cone 29 and the hub of the clutch sleeve 28 tends to hold the former disengaged from the latter.

The rear end of each plow beam 9 is connected to the lower end of a plow lifting cable 33. The cables 33 are attached to and adapted to be wound upon drums 34 secured 25 to the shaft 26. All of the said cables 33 except the one at the extreme left, also run over idle guide sheaves 35 journaled in suitable bearings 36 on the overlying oblique rear portion of the frame 1.

30 Mounted in suitable bearings on the frame 1 and extended transversely of the shaft 26, just at the rear of the clutch cone 30 is a rock shaft 37 that is provided with five arms 38, 39, 40, 41 and 42. The arm 40 works 35 against the grooved hub of the clutch cone 30. The arm 38 is connected by a link 43 to the lower end of an operating lever 44 that is intermediately pivoted to the frame 1. The arm 39 is connected by a link 45 to a 40 tripping lever 46 pivoted to the rear portion of the frame 1 with its depending end in position to be engaged by one of the plow beams 9 (see Fig. 2) when the plow beams are simultaneously raised. The arm 41 is 45 connected by a rod 47 to a retaining pawl, 48, pivoted to a bearing 49 secured on the frame 1. This retaining dog 48, as shown, is provided with a single tooth that is engageable with laterally projecting teeth 50 of the 50 peripherally toothed ratchet 51 rigidly secured on the shaft 26.

The numeral 52 indicates a hand-operated lever journaled on the shaft 26 adjacent to the ratchet wheel 51 and provided with a 55 normally retracted driving dog 53 that is adapted to engage the peripheral teeth of the said wheel 51 when it is desired to lift the plows by hand. The front end of the rod 47 is passed loosely through a perforation in the arm 41 and the said arm, when moved forward, is engageable with a stop collar or head 54 on the said rod, and when moved in the other direction, depresses a spring 55 which is anchored to the said rod 60 at its front end.

The arm 42 of the rock shaft 37 is connected by a link 56 (see particularly Fig. 6) to a dog carrier 57 mounted to slide on a shipper bar 58. This shipper bar 58, at one end, is rigidly secured to a shipper lever 59 which, at one end, is pivoted to the frame 1, as shown in Fig. 1 and at its intermediate portion operates on the grooved hub 60 of the windlass drum 23. The shipper bar 58 has a single notch, as shown in Fig. 6 that is 75 normally engaged by a dog 61 pivoted to the dog carrier 57 and having a long end 61^a.

The numeral 62 indicates a tripping rod which, at its lower end, is pivotally connected to one of the plow beams 9 and at its 80 upper end works freely through a perforation in the said arm 61^a and is provided with a tripping collar 62^a that is engageable with the said arm.

On the plow adjusting cable 21, already 85 described, is a stop 63, which, as shown, is of conical or wedge shape form, and is engageable with a beveled lock lug 64 on the depending end of a lock lever 65 that is intermediately pivoted to the bearing 24 to 90 which the sheave 22 is journaled. The other end of this lock lever is connected to the lower end of an upwardly spring-pressed tripping rod 66 having at its upper end a foot piece 67 guided by a bearing on the 95 frame 1 (see particularly Fig. 3). The shaft 25 is adapted to be continuously driven from the engine 5 through the transmission mechanism 7 and through a driven worm 68 and a cooperating work gear 69 on the front 100 end of the said shaft 25.

Operation: The operation is substantially as follows: When the plows are in the ground, very great force is required to lift the same, because of the weight of the dirt 105 thereon and because the plows in rising, must tear their way through the ground. With my improved adjusting mechanism, this is obviated by first raising the front ends of the plow beams so that the plows, 110 under forward movement of the tractor, will first cut their way out from the ground to the top of the soil, and then the plows are lifted by a comparatively small power after they are brought to the surface of the 115 ground. This is accomplished by power afforded by advance movement of the machine and under control of the operating lever 44. This action specifically described is as follows: Normally, the lever 18 will 120 rest on the stop bolt 20, and the depth at which the plows will work in the ground may be regulated by adjustments of the said bolt in the perforations of the segment 19. When it is desired to raise the plows, the 125 upper end of the operating lever 44 is moved rearward or toward the left in respect to Figs. 5 and 6. The effect of this movement is to tend to engage both of the clutch cones 29 and 30 with the continuously driven clutch 130

sleeve 28, by means of the arms 40, 42 but the arrangement is such that the rocking movement of the shaft 37 operating through the link 56, dog 61, bar 58 and lever 59 will 5 engage the cone 29 with the said sleeve before the cone 30 has been pressed into frictional engagement with said sleeve. When the said cone 29 is thus engaged by the sleeve 28, it temporarily prevents the engagement 10 of the cone 30 with said sleeve, but it instantly throws the drum 23 into action by winding on the cable 20, rocks the shaft 17, and simultaneously raises the anchor blocks 13, and hence, the front ends of the plow 15 beams 9. Just before the front ends of the plow beams reach their extreme uppermost positions, the lock 63 on the cable 20 forces aside and then engages above the lock lug 64 of the lock lever 65, and hence cooperates 20 therewith to prevent the front ends of the plow beams from being again lowered until released by stepping on the foot piece 67. Just as the said anchor blocks 13 reach their 25 extreme uppermost positions, the collar 62^a of the rod 62 strikes the arm 61^a of the dog 61 and releases the latter from the shipper bar 58. This releases the clutch cone 29 and permits the spring 32 to instantly throw the same out of frictional engagement with the 30 clutch lever 29, thereby stopping further winding movement of the cable 20. This leaves the front ends of the plow beams locked in their uppermost adjustment, which adjustment causes the plows to pull 35 themselves out of the ground under advance movement of the machine. The instant that the dog 61 is unlocked from the shipper bar 28 and the clutch cone 29 and drum 23 released, as just above described the said cone 40 no longer operates as a stop to prevent engagement of the cone 30 with the said clutch sleeve 28, and hence, continued downward pressure on the lever 44 will cause the clutch cone 30 to engage the said continuously 45 driven sleeve 28 and throw the shaft 26 and windlass drums 34 into action; and this will cause the cables 33 to wind up and lift the plows above the ground. When the plows have been lifted to their highest positions 50 above the ground, one of the plow beams 9, striking the lever 46 will throw the rod 45, rock the shaft 37 and arm 40 in a direction to disengage the clutch cone 30 from the driven clutch sleeve 28, and thereby stop 55 the winding action of the said cables 33. As the plows are being thus lifted, the dog 48 operates on the lateral teeth 50 of the ratchet wheel 51 serving to hold the plows in their elevated positions. The said retaining dog 48 is adapted to be released when

it is desired to drop the plows to the ground by movement of the upper end of the lever 44 forward, so as to cause the arm 41 to engage the head 54 of the rod 47. Thus it will be seen that the several movements required, 65 first to work the plows out of the ground, and then to lift the same, is accomplished by a movement of the lever 44 in one direction, and that the return of the plows to working positions is accomplished by imparting a reverse movement to the said lever 44 and by stepping on the foot piece 67 of the tripping rod 66.

The plow adjusting and lifting mechanism described has, in actual practice, been 75 found highly efficient and very convenient for the purposes had in view.

What is claimed is:

1. The combination with a truck, of a plow having the front of its beam connected 80 to said truck, a beam-lifting connection between the front end of said plow beam and truck including an operating clutch, a plow-lifting connection between said plow and truck including a second operating clutch, a 85 motor with connections for transmitting power to the said two operating clutches, a clutch controlling lever with connections for throwing said two clutches into and out of action, and an automatic trip operating to 90 release the first operated clutch and to permit the other clutch to be thrown into action.

2. The combination with a truck and an engine carried thereby, of plows having 95 beams connected to the truck frame with freedom for pivotally raising and lowering movements and for vertical adjustments of the front ends of said beams, of means for vertically adjusting the front ends of the 100 plow beams and for raising the plows bodily, said beams comprising two engine driven clutches, and a controlling lever with connections for throwing said clutches into action, the first engaged clutch serving to 105 hold the other temporarily out of action, and the said connections including an automatic trip for releasing the first operated clutch and thereby permitting the second clutch to be thrown into action, the first 110 operated clutch serving to vertically move the front ends of said plow beams and the second actuated clutch serving to raise said plows bodily from the ground.

In testimony whereof I affix my signature 115 in presence of two witnesses.

JOHN A. ANDERSON.
